UNITED STATES PATENT OFFICE.

JOSEPH M. SCHUTZ, OF CHICAGO, ILLINOIS, ASSIGNEE TO SCHUTZ HAWLEY COMPANY,
OF CHICAGO, ILLINOIS, A CORPORATION OF ILLINOIS.

CARBURETING AIR FOR INTERNAL-COMBUSTION ENGINES.

1,397,744.

Specification of Letters Patent. Patented Nov. 22, 1921.

Application filed May 6, 1918. Serial No. 232,765.

To all whom it may concern:

Be it known that I, JOSEPH M. SCHUTZ, a citizen of the United States, and a resident of Chicago, county of Cook, and State of Illinois, have invented certain new and useful Improvements in and for Carbureting Air for Internal-Combustion Engines, of which the following is a specification.

My invention relates to improvements upon and applicable to internal combustion engines that derive their power from charges of gas, kerosene, gasoline, alcohol, or the like in explosive admixture with air.

The object of my invention is to increase the capacity, efficiency, and durability of such engines by improving the character of the explosive charges supplied thereto. This I accomplish by freeing the air from dust particles which would cause excessive wear if admitted to the engine, and by insuring the complete vaporization of all the fuel entering into admixture with the dust-free air. As will appear, these two operations take place simultaneously, being accomplished in a single device which preferably is a joint part of the admission and exhaust manifolds of the engine.

My invention comprehends the use of an air-and-fuel mixing valve or carbureter of any desired form whether of simple or complicated structure. Starting with such an air-and-fuel mixer (hereinafter called a carbureter) I interpose between it and the admission ports of the engine a device which serves to first reject and finally to retain any dust (particles of dirt and grit) that may enter with the air, and which also serves to first reject and then positively vaporize and return to the main stream the fuel particles that escape from the mixer in an unvaporized state; whereby only a mixture of clean air and dry fuel vapor is supplied to the engine cylinders.

I accomplish these important effects by interrupting the stream of mixture after it leaves the carbureter and there straining out or rejecting both the particles of dust and of unvaporized fuel present in the initial stream. Simultaneously, by the application of heat, not to the air and its burden of already vaporized fuel but to the rejected particles, I accomplish the vaporization of the rejected fuel and its re-addition to the main stream in the form of hot dry vapor, while

collecting and retaining the dust against entrance to the inlet ports of the engine. The heat required may be most conveniently derived from the exhaust gases of the engine, and for this reason I have incorporated my device with the exhaust passage or manifold thereof.

In treating the initial or crude explosive mixture in the manner described, I correct the deficiencies of the carbureter whatever its kind. For an understanding of this corrective effect, it is necessary to first consider the nature and operation of the initial air and fuel mixer, to-wit, the carbureter. The air needed for the mixture is sometimes blown through the carbureter, but more frequently is drawn through it by the action of the pistons in the engine cylinders. In either case the proper function of the carbureter is to supply in the varying quantities demanded an explosive mixture composed of relatively predetermined quantities of liquid and air in a predetermined ratio.

In stationary practice, where the engine speeds are substantially constant, it is possible to accurately adjust the carbureter and secure a substantially constant or invariable, though not always completely vaporized, explosive mixture, except to the extent that the latter is effected by atmospheric conditions or a change of fuel. In contrast, engines used in automobiles and air-planes call for rapid variations in the operation of the mixture-forming device. The best that the present carbureters can do is to perform ideally under ideal conditions. Every change of engine speed;—every movement of the engine throttle;—every change in the quality of the fuel;—every change of altitude;—every variation of atmospheric humidity;—and every change of atmospheric temperature, causes a departure from the ideal operation.

Few mixing valves or carbureters now in use are of that simple construction that would seem sufficient for the mere supply of air and fuel in a fixed ratio;—instead various internal devices have been added, with a view to correcting not for all but for some of the more violent of the varying conditions encountered in use. I know of no present valve or carbureter that serves the engine equally well under all speeds and conditions. Upon analyzing the performance of such car-

bureters, it will be found that the fault lies not so much in the failure to supply or even to atomize the requisite quantity of fuel, but rather in the failure to vaporize all of the fuel supplied, so that it may enter into explosive admixture with the air in advance of its admission to the engine cylinders.

Where the fuel used is high-grade gasoline, the specific heat of the air passing through the carbureter is often adequate for the substantially complete vaporization of the fuel, but let the engine speed be changed, or any other vital condition be altered, or a more difficultly vaporizable fuel be substituted and immediately there ensues a failure to completely vaporize the fuel and consequent falling off in engine efficiency and reliability, to say nothing of the difficulties which are occasioned by the entrance of liquid fuel in cylinders of the engine.

It is evident that these failures or deficiencies of the carbureter should be obviated. This appears to be beyond accomplishment within the carbureter itself, hence my provision of a correcting device which is auxiliary to the carbureter and which may be relied upon to vaporize the fuel whatever its kind and under all conditions, the device serving to deprive the initial or crude product of the carbureter of its varying burden of unvaporized fuel and utilizing the always superabundant heat of the exhaust gases to instantly vaporize the extracted fuel and return it to the stream of air and initially vaporized fuel.

An important incident of the corrective vaporizing operation is the raising of the temperature of the completed mixture by just so much heat as is taken from the exhaust gases to vaporize the rejected fuel. The heat thus added is not enough to detrimentally rarefy the air content of the mixture and is of marked advantage in that it prevents condensation of the fuel and insures the prompt and complete combustion of the mixture when fired or ignited in the engine.

Whatever dust passes through the carbureter with the air, augments the mere atomization of the fuel and tends to defeat the initial vaporization thereof, and this accentuates the necessity for my improvement; and, as will appear, renders its operation more certain and effective.

My invention will be readily understood on reference to the drawings that form part of this specification and in which: Figure 1 is a side elevation of an engine equipped with a device embodying my invention;—Fig. 2 is a view substantially on the line 2—2 of Fig. 4;—Fig. 3 is a plan view of the engine shown in Fig. 1, the same being partly in section on the line 3—3 of Fig. 1;—Fig. 4 is a view partly in section and

partly in elevation, the part in section being substantially on the line 4—4 of Fig. 2;—Figs. 5 and 6 are respectively side and end elevations of a modified form of my invention, the engine being of the type having its inlet and exhaust manifolds upon the same side;—Figs. 7 and 8 illustrate a further form of my invention, Fig. 7 being a section on the line 7—7 of Fig. 8, and Fig. 8 being a section on the line 8—8 of Fig. 7;—Fig. 9 is a plan view illustrating my invention in still another form;—Fig. 10 is a side elevation thereof;—Fig. 11 is a view substantially on the line 11—11 of Fig. 10;—and Fig. 12 illustrates a modified arrangement of the dam which I use in the mixture intake passage.

My invention is applicable to internal combustion and explosion engines of all types which employ air and fuel mixers. The essentials are substantially the same for all engines, but, as herein shown, the complete device in each case preferably includes an exhaust manifold or passage and therefore takes its individual form from the engine to which it is appropriated.

For convenience, I shall refer to the essential elements of the invention by the same reference characters throughout the drawings, and shall differentiate the auxiliary parts by reference numerals individual thereto in the several structures shown.

The part marked A, is a mixing valve or carbureter, of any desired form or type, adapted to admit air and fuel to the intake passage of the engine. The carbureter, A, has the usual throttle valve, B, and constitutes the intake end of the passage or manifold through which the engine is supplied with the explosive mixture initiated in the carbureter. As here shown, the carbureter is of the suction type, the air being drawn through it and through the intake manifold by the action of the pistons in the cylinders of the engine, this being preferable, as the partial vacuum maintained in the manifold facilitates the operation of my device. The invention, however, may be successfully employed upon an engine that has a blower or pump that forces air through the carbureter to assist the piston action. As before stated, the device is interposed between the carbureter and the intake ports of the engine; that is, it constitutes a part of the intake passage or manifold; and, it also constitutes a part of or is incorporated with the hot gas exhaust manifold of the engine from which the needed heat is derived.

On passing the throttle valve B, the crude mixture enters a tube, C, which has its counterpart in a tube, D, both being parts of the intake-passage or manifold. As shown, the ends of the tubes C and D are separated by a gap, E. The length of this gap is such as to afford an opening of an

area that approximates the sum of the cross-sectional areas of the two tubes, C and D. In this gap is an imperforate dam or baffle, F, preferably co-axial with the tubes, C and 5 D, and of about the same diameter.

The stream of mixture on emerging from the tube, C, must pass the dam, F, in order to enter tube, D. Thus the stream is subjected to sudden interruption and expansion 10 and is caused to bulge out around the dam, F. Under the effect of a partial vacuum in the intake manifold the stream takes the shortest path around the dam, D, and hence assumes approximately the form or outline 15 indicated by the dotted lines, F', in several figures of the drawings. In this passage from the tube, C, to the tube, D, and by reason of the sudden deflection of the stream, all particles of dust and of liquid fuel 20 carried by the stream are thrown out or rejected, and thus prevented from entering the tube, D, as more fully explained hereinafter.

Inclosing the gap, E, is a chamber, G, formed by walls which are so remote therefrom as to be entirely beyond the reach of the bulging stream of mixture in the gap, E. The particles of dust and liquid rejected at the gap, E, therefore pass through a void (between the exterior of the bulging stream 30 and the walls of the chamber, G) and are deposited upon said walls. These walls of the chamber, G, are in turn inclosed by a chamber, H, that is in communication with or which is a part of the exhaust manifold 35 of the engine. Hence the walls of the chamber, G, are normally maintained at a high temperature, and all particles of liquid fuel which land thereon are instantly vaporized. The hot vapor thus generated occupies the void before mentioned, and, obviously, returns to the main stream of mixture through that portion of the gap, E, which lies between the top of the dam, F, and the lower end of the tube, D. Meantime the dust 40 remains in the chamber, G, for it is not disturbed by the sweep of air or mixture through the gap, E, being separated therefrom by a space in which there is little movement. In consequence, the dust is retained 45 in the chamber, G, and gradually accumulates in the bottom thereof.

When heavy or impure fuel is used, a quantity of coked residue is added to the accumulation for some of the constituents of 50 such fuels do not vaporize at the temperatures attained by the walls of the collecting and vaporizing chamber.

To permit the occasional cleaning of the chamber, G, (the removal of the accumulated dust and residue) I make the tube, C, removable from the chamber, G, providing it with a flange, C', which is bolted on or otherwise detachably secured to the bottom of said chamber; and, as shown, in Figs. 10 60 and 11, the bottom of the chamber, G, may

be provided with clean-out holes, G', closed by removable plugs, G'', for the same purpose.

Preferably, the chamber, G, is made of much greater size than would be needed 70 merely to surround the gap, E, and insure the vaporization of the rejected fuel particles, drops or globules. This greater size is required to provide a superabundance of heating surface and to give the chamber 75 sufficient capacity as a dust or residue collecting pocket. Hence the chamber, G, is shown to extend somewhat above the lower end of the tube, D, and far below the top of the tube, C. 80

The middle portion, G^a, of the vaporizing and collecting chamber is preferably of the greatest diameter, as this is directly opposite the gap, E, and it is needful that the hot walls shall be remote from the column of air 85 and vapor sweeping past the dam, F. If close contact were permitted the air would be directly raised in temperature, to do which is not only unnecessary, but also detrimental. The upper portion, G^b, and the lower portion, G^c, of the chamber, G, may be of smaller diameter, as these cavities are relatively remote from the gap, E. The upper portion, G^b, serves as a trap to prevent the escape of vapor particles into the tube, D, in 90 advance of their complete vaporization. The lower cavity or portion, G^c, is in effect a vacuum cavity, being tightly closed at the bottom and receives the dust which is initially collected in the larger portion, G^a. 95 The wall, G^h, between the chambers, G and H, obviously takes its shape from the desired form of the chamber, G. This wall presents a surface which is kept hot substantially from the top to the bottom of the 105 chamber, G, by the hot exhaust gases from the engine circulating about the wall, G^h, with that portion of the exhaust manifold which includes the chamber, H.

It is of distinct advantage that the hot 110 wall, G^h, is remote from the tube, C, the result being that the mixture is little, if at all, heated during its passage through the tubes, C and D, except to the extent that its temperature is raised by the addition of hot 115 vapor that may be evolved in the walls of the chamber, G.

Turning now to those parts and formations which are merely incidental and auxiliary to my device:— 120

Attention is first directed to the different forms of the wall, G^h, as depicted in the several figures of the drawings. As shown in Figs. 1 to 4, the upper part, 2, of the wall, G^h, projects above the top of the external 125 heating chamber, H, to avoid as far as possible the conduction of heat shown in Figs. 5 and 6 and 9 to 12, whereas in Fig. 7, which illustrates the device as made for use with a simple engine, or with a separate heater, the 130

whole wall, G^h , is shown to be exposed with in the heating chamber, H .

As illustrated in Figs. 2, 4, and 12, the bottom of the large vaporizing space, G^x , is rather abrupt and presents a substantially sharp corner, 3, where it emerges with the lower cavity, G^z ;—the better construction is illustrated in Figs. 7, 10 and 11, the wall portion, 4, being there steeply pitched to allow the freer fall of both liquid drops and dust that collect on the hot surface.

The lower part, 17, of the wall, G^h , may be, and preferably is, flared outward toward the bottom, as shown in Figs. 10 and 11, the purpose being two-fold: to enlarge the cavity, and to facilitate the removal of the tube, C , when the cavity is full of gummy residue.

The dam, F , may be supported in various ways, as by the central stem, 5, shown in Figs. 2, 4, and 7; but preferably by a movable part, 7 or 8, as shown in Figs. 9 to 12; both of which arrangements permit the dam to be swung out of the way at moments of starting the engine. This last is a precaution and need be observed only in the case of engines not provided with self-starters. In such cases it is desirable to avoid momentarily depriving the mixture of a part of the fuel required to start the engine easily. The device shown in Figs. 9 to 11 comprises an arm, 7, fixed on a vertical shaft, 9, extending through the flange, 10, of the tube, D , and having a crank arm, 11, on its upper end; whereby the dam, F , may be swung to one side out of the path defined by the tubes C and D . A combined end thrust and torsion spring, 12, serves to hold the shaft and disk, F , in normal position, there being a stop, 13, (see Figs. 9 and 10) which engages the arm, 11, and fixes that position. The dam-shifting device, 8, shown in Fig. 12 comprises a central shaft which carries the dam, F , and which may be rotated after the manner of a throttle valve. A crank arm, 14, is provided for this purpose and on the shaft, 8, is a stop cam, 15, coacting with a spring pawl, 16, to secure the dam in one or the other of its positions. The engine illustrated in Figs. 1 to 4 is of the kind having its inlet and exhaust ports in opposite sides of the cylinders; and hence the exhaust manifold, 18, on one side and the intake manifold on the other side. The latter is within the engine block, and only its inlet opening, 19, is shown. The connection between this opening and the tube, D , of my device comprises a tube or duct, 20, which arches across the top of the engine, and which like the tubes C and D become a part of the intake manifold or passage. Chief interest attaches to the manner in which my device is incorporated with the exhaust manifold, 18. On the top of the manifold appears the portion, 2, of the wall, G^h , of my device. On the bottom of the mani-

fold, there is a circular pot-like wall, 21, which is the outer wall of the chamber, H , before referred to. The upper part of the heating chamber emerges with the interior, 22, of the manifold proper, 18. Obviously, the hot gases from the exhaust ports, 23, of the engine impinge upon and circulate about the wall, G^h , before escaping through the outlet, 24, that leads from the portion, 21, of the manifold. As shown, the walls, 2, G^h , and 21, are integral with the walls of the manifold proper, the whole comprising a single casting.

The device comprising the combined exhaust manifold and vaporizer which appears in Figs. 5 and 6 is of substantially the same construction as shown in Figs. 1 to 4; but in this case the admission manifold, 25, is directly above the exhaust manifold, 26; on the same side of the engine. It is therefore only necessary to provide a short connection, 27, through which the corrected explosive mixture may pass from the collecting and vaporizing chamber directly into the admission manifold, 25.

Much the same arrangement is observed in Figs. 9 to 11;—the intake manifold, 28, being again directly above the exhaust manifold, 29; but in this case the manifold, 28, is provided with a flanged intake, 30, suitably packed upon and bolted directly to the flange, 31. The complete device is also distinguished from the others by the presence of the integral exhaust outlet, 29', terminating at a point or position, 32, which is common to many engines now in use.

The device shown in Figs. 7 and 8 is adapted to be coupled into the exhaust pipe of an engine at any desired point without special regard to the arrangement of the ducts immediately identified with the ports of the engine. To this end the heating chamber, H , is inclosed by a cylindrical shell, 33, the hot exhaust gases entering into the top through the tangential intake, 34, and leaving at the bottom through a similar tangential outlet, 35.

I have herein shown only the best embodiments of my invention which I have thus far devised. The invention is not limited thereto, nor to the specific manner in which it is here shown to be related to the other parts of the engine. Various modifications will suggest themselves to one who is skilled in the art and are comprehended by my invention, as pointed out in the appended claim.

My invention is of special utility in airplane service although in that service the function of the device as a dust collector is of less importance. With the air-plane it is especially necessary that all of the fuel supplied by the mixing valve or carburetor shall be properly vaporized before entering the cylinders of the engine and that no failure

shall result from the different conditions under which the engine is called upon to operate. This my device accomplishes and therefore frees the air-plane engine from 5 many well-known present limitations, particularly in that it permits the employment of heavier and less inflammable fuels, and enables the engine to operate reliably and efficiently at different altitudes, and atmospheric temperatures.

In use my invention meets and nullifies conditions that would work a failure if the ordinary carbureting devices alone were relied upon. In my device the vaporization 15 of the liquid fuel is as complete at low throttle and at low engine speed as under high speed conditions. The temperature of the mixture as it enters the intake ports of the engine varies with the quality of fuel 20 employed and in proportion to the quantity thereof rejected from the initial stream to be vaporized upon the hot walls of the compensator. Any change of throttle opening accomplishes a corresponding alteration in 25 the temperature of the completed mixture, usually increasing as the throttle opening is increased and diminishing as the throttle opening is lessened, for as the volume of mixture is reduced the temperature of the 30 exhaust gases is lowered, less fuel is vaporized on the walls of the compensator, and less heat added to the product flowing from the device. The heaviest of engine fuels are readily vaporized within the device, especially 35 as aided by the partial vacuum ordinarily existing therein. That lessening of the quantity of heat in the exhaust gas passage, which follows the throttling of the intake causes no failure of vaporization, for 40 under such conditions there is always a higher vacuum in the intake manifold which off-sets the lack of heat in the heating chamber. These advantages are preserved even when a blower, used to feed air to the carbureter, partly negatives the pumping action 45 of the engine pistons.

With reference to the action of my device as an air purifier, it is important to note that instead of attempting to strain the air before it enters the carbureter I allow the 50 dust to pass through that device and become wet with atomized fuel. Thus two important temporary effects are obtained; to-wit, the weight of the dust particles is increased, and reversely many small globules of fuel 55 are caused to collect upon the dust particles, thus making larger liquid globules. Thereby, the centrifugal or tangential separation of the particles is positively insured at the gap or interruption in the intake passage, 60 and once discharged from the stream of mixture all such particles are certain to be caught upon the hot walls of the vaporizing-and-collecting chamber.

Having thus described my invention, I 65 claim as new and desire to secure by Letters Patent:—

The improvement herein described comprising an internal combustion engine, in combination with an intake passage leading 70 to the engine and an exhaust passage leading from the engine, means at the far end of the intake passage for supplying a stream of mixture of air and liquid fuel under the suction of the engine, such intake passage 75 having an opening intermediate its ends, and constructed to deflect or turn the stream of mixture from its course at that point, whereby to eject unvaporized particles of liquid and dust, a closed chamber surrounding said 80 opening in the intake passage, in position to receive the particles ejected from the stream of mixture but presenting walls so far removed from the flowing stream of mixture as to be wholly out of contact therewith, and a heating jacket surrounding said 85 walls of the chamber and connected with said exhaust passage, substantially as described.

In testimony whereof, I have hereunto set 90 my hand this 29th day of April, 1915.

JOSEPH M. SCHUTZ.
